Application November 10, 1932, Serial No. 641,987

29 Claims. (Cl. 230—46)

This invention relates to compressors.

More particularly, this invention relates to fluid compressors which compress air or gas from any given pressure to a relatively higher pressure. The compressors may be of any type including those of the double acting, single and multiple stage types, and those of the multiple cylinder single stage type, operated to produce either a vacuum or to increase pressures above atmospheric pressure, and may be driven by any type of prime mover.

An object of my invention is to provide a new means for compressing a fluid, a new compression cycle characterizing the operation, and a new compressor embodying the principles of my invention.

According to my invention, I provide a compressor, which when compared to the conventional or prior art type of compressor, greatly decreases the usual losses due to the expansion of the unexpelled compressed fluid remaining in the clearance volumes after delivery has ended, suddenly reduces the pressure in the clearance spaces after delivery has ended, spontaneously super-charges the new charges to be compressed, greatly increases the volumetric efficiency, and increases the isothermal compression efficiency.

A further object according to my invention, is to provide compressors which when operated at constant speed, with means to vary the quantities delivered exactly in proportion to the demand for air or gas in quantities varying in increments from 100% of full capacity down to zero capacity, and at the same time, consuming power approximately in proportion to the quantities delivered.

The accompanying drawings show one representative embodiment of my invention. Its principles may be applied in various ways without departing from the invention, as comprehended by the scope of the appended claims.

Fig. 1 is a side elevation of one form of my invention, partially in vertical central section terminating at the inlet and discharge openings.

Fig. 2 is a detail cross-sectional view, taken on line 2—2 of Fig. 1, and on a radial plane approximately at right angles to the plane of the section shown in Fig. 1. Fig. 2 shows the piston advanced toward the left as compared with its position in Fig. 1.

Fig. 3 is a side elevation partially in vertical central section, showing a complete assembly of a vertical, two cylinder, single acting belt driven compressor embodying my invention, independ-

ent of my variable capacity control and regulating equipment.

Fig. 3a is a sectional plan view through the cylinder head block of Fig. 3 above the valves.

Fig. 4 is a diagram of the compression cycle typifying the operation of the conventional or prior art type of compressor.

Fig. 5 is a diagram of the compression cycle embodying my invention, independent of the variable capacity features.

Fig. 6 is a diagram showing two compression cycles, similar to those shown in Fig. 5, harmonizing the operation of a single cylinder, double acting compressor embodying my invention, independent of the variable capacity features.

Fig. 7 is a diagram showing two compression cycles harmonizing the operation of a single cylinder, double acting compressor embodying my invention in compressors delivering at rates of capacity less than full rated capacity.

Fig. 8 is a side elevation of the compressor shown in Fig. 1, and shows one form of a complete assembly including the variable capacity regulating and control equipment embodying my invention.

Fig. 9 is a transverse partial horizontal sectional detail of a by-pass interconnecting the two respective opposite ends of the compressor cylinder, and includes the control valve shown in Fig. 8 of this complete arrangement embodying my invention.

Fig. 10 is a partial vertical sectional detail of the pressure regulating control of Fig. 8, laid horizontally.

Referring to Figs. 1 and 2, a single cylinder, single stage, double acting, direct connected, motor driven compressor is shown in which, the cylinder 1, the head end head plate 2, and the crank end head plate 3 are bolted together and to the frame 4. In the description which follows, reference to bolts obviously needed to bolt stated parts together will not be made. The crank shaft 5 is supported at one end by bearings mounted in the frame 4, and at its opposite end by an outboard bearing in accordance with the usual practise. The rotor of the motor 6 is mounted directly on the crank shaft 5 and transmits the power for operating the compressor by way of rotating the counterweighted crank 7 which is secured to the crank shaft 5 by the key 8. The crank pin 9 is also firmly attached to the counterweighted crank 7 and is rotated by the crank shaft 5. The connecting rod 10 transmits motion from the crank pin 9 to the cross-head 11 which reciprocates the piston rod 12.

and the attached piston 13. The piston 13 is provided with the usual piston rings 14, 15, to reduce the leakage past the piston 13 to a minimum as it is reciprocated in the cylinder 1.

5 The inlet pipe opening 16 connects with the chamber 17 from which the inlet stream of fluid to be compressed is divided to alternately pass through the respective inlet passages 18, 19 leading to the inlet valve chambers 20, 21 respectively. The inlet valve 22 is positioned in the head plate 2 and held in place by the bonnet 24 and the stud 26. The inlet valve 23 is positioned in the head plate 3 and held in place by the bonnet 25 and the stud 27. Preferably, I employ automatic inlet valves 22, and 23 of the standard plate type of construction which depend for their opening and closing entirely upon pressure differences so as to admit air or gas to the cylinder 1 through the heads 2, 3 and prevent its return 10 from the cylinder 1 when being compressed.

15 The discharge valves 28, 29 are also preferably of the standard construction plate type of automatic valves positioned respectively in the heads 2, 3 and retained in position by the bonnets 30, 31 and the studs 32, 33 respectively. The discharge valve 28 associated with the valve chamber 34 and the passage 36, and the discharge valve 29 associated with the valve chamber 35 and the passage 37, which valve chambers join 20 in the compartment 38 to which the discharge pipe 39 is attached. The discharge valves 28, 29 are provided to automatically permit the discharge of compressed air or gas from the cylinder 1 under the condition that its pressure exceeds that of the discharge line 39, and to prevent the return of fluid to the cylinder on the suction strokes of the piston 13. The discharge valve 28 is provided with the seat section 40 and the guide section 41 so as to control its limits of movements when opening and closing. The control parts of the discharge valve 29 are similar in construction to those of the discharge valve 28. The inlet valves 22, 23 are preferably similar in construction to the discharge valve 28, but positioned so as to operate in the reverse direction of travel of fluid to that of the discharge valves 28, 29.

25 For cooling the parts, I provide the water jacket 42 in the head plate 2, the water jacket 43 in the cylinder 1, and the water jacket 44 in the head plate 3.

30 Referring to Fig. 2, the piston 13 is shown at or near its extreme position of travel toward the head plate 2 thus leaving the space indicated adjacent the port 45 between the cylinder 1, the head plate 2, the inlet valve 22 and the discharge valve 28 which is called the clearance space, or clearance volume, or compression compartment, at the head end of the cylinder 1. Likewise, there will be a clearance space, or clearance volume or compression compartment indicated adjacent the port 46 between the piston 13 and the head plate 3 operative when the piston 13 has travelled to its extreme position at the crank end of the cylinder 1. In each of these clearance spaces, and in all prior types of compressors, an unexpelled charge of compressed fluid remains in the clearance volume after the normal expulsion or delivery of the compressed fluid has been completed at or near the end of each stroke of the piston. The trapping of some of the compressed fluid in the clearance space, when re-expanded to intake pressure, is equivalent to a certain amount of free air at inlet conditions which is not delivered by the compressor.

35 This re-expansion of the unexpelled compressed fluid which remained in the clearance space ensues for and consumes a considerable portion of the return stroke of the piston before the pressure in the cylinder has become reduced to permit the opening of the inlet valves which depend for their opening and closing entirely upon pressure differences. This clearance volume expansion causes a late opening of the inlet valves which greatly reduces the quantities sucked into 40 the cylinder to be compressed, and also greatly reduces the net delivered capacity of compressors operating according to these principles, and is a primary reason why the average industrial compressor of the prior type delivers only from 45 40% to 80% of its piston displacements, depending upon its size, and the pressure differences to which the fluid has been compressed. The ratio between net delivery and piston displacement determines the volumetric efficiency of the 50 compressor.

55 According to my invention, I provide the passage 47 having the ports 45 and 49 at the head end of the cylinder 1 to form a by-pass about the piston 13 and interconnect the clearance space with the interior of the cylinder 1 on the opposite side of the piston 13 when the piston 13 has most nearly approached the head 2 at or near this end of its stroke. Likewise, I provide the passage 48 having the ports 46 and 50 at the crank end of the cylinder 1 to form a by-pass about the piston 13 and interconnect the clearance space with the interior of the cylinder 1 on the opposite side of the piston 13 when the piston 13 has most nearly approached the head 3 at or near the other end of its stroke. The piston 13 covers and uncovers the ports 49 and 50 as it travels and reverses its direction of travel at or near the respective ends of its strokes. The ports 49, 50 are positioned in the interior walls 40 of the cylinder 1 at locations immediately adjoining the piston 13 on its sides opposite the clearance space when the said piston 13 is at or near the respective ends of its strokes. The ports 49, 50 may be rectangular in shape of opening into the cylinder 1, and positioned with the longer sides of the respective rectangles in planes parallel to the faces of the said piston 13. The number of passages 47, 48 and the respective ports is such as to provide any desired capacity to 50 become fully effective in aggregate area of openings at each of the respective ends of the cylinder 1 with a minimum travel of the piston 13. Expulsion of compressed fluid is terminated just prior to the end of each stroke of the piston 55 13 due to the opening of the ports 49, 50 by the travel of the piston 13. The uncovering of the port 49 by the piston 13 in its travel toward the head 2 at or near the end of its stroke by-passes the fluid about the piston 13 and effects a flashing over of the unexpelled compressed fluid from the clearance space 45 through the passage 47 and the port 49 into the interior of the cylinder 1 which at this stage is being filled with a new charge of fluid at inlet pressure. Likewise, the uncovering of the port 50 at the opposite end of the cylinder 1 by reverse travel of the piston 13 in the direction of the head 3, by-passes the fluid about the piston 13 and effects a flashing over of the unexpelled compressed fluid from the clearance space 46 through the passage 48 and the port 50 into the interior of the cylinder 1 which at this stage is being filled with a new charge of fluid at inlet pressure. These alter- 70 75

nating flash-overs from the clearance spaces at or near the respective opposite ends of the strokes of the piston 13 effect a sudden and partial compression of the respective new charges which have been sucked into the cylinder 13, and as these initiatory compressions are effected prior to the beginning of the respective compression strokes of the piston 13, and entirely independently of extra valves, extra cylinders, and do not require auxiliary compression chambers, the phenomena is herein defined as spontaneous super-charging. The flashing over of the compressed fluid from the clearance space into the cylinder 1 reduces the pressure in such clearance space and equalizes the pressures on the opposite sides of the piston 13 at the pressure to which the new charge in the cylinder 1 has been raised as a result of the spontaneous super-charging of the said new charge.

Travel of the piston 13 toward the crank end head plate 3 covers the port 49 and closes the passage 47 thus preventing further communication at this time between the clearance space within the cylinder 1 between the piston 13 and the crank end head plate 3. Simultaneously, compression from the previously resultant partial or initiatory compression begins in the cylinder 1 between the piston 13 and the crank end head plate 3, and also, re-expansion of the reduced pressure volume begins on the opposite side of the piston 13 in the crank end clearance space. The pressures on the opposite sides of the piston 13 are equalized up to the point of the closing of the port 49 by the piston 13. The closing of the port 49 and the re-expansion of the reduced pressure volume in the head end clearance space, which now includes the volume of the passage 47, requires much less travel of the piston 13 in proportion to the whole stroke of the piston 13 than similar travel of the piston in a prior art conventional type of compressor in which the clearance volume is re-expanded from the relatively higher discharge pressure. Therefore, according to my invention, the opening of the inlet valves 22 and the consequent beginning of the suction portion of the stroke occurs markedly earlier than in the prior type, which feature of my invention results in improved volumetric efficiency.

As the piston 13 approaches the crank end of the cylinder 1, compression is completed and expulsion takes place while the piston 13 covers the port 50 of the passage 48. Further travel of the piston toward the head plate 3 now uncovers the port 50, discontinues expulsion, establishes communication between the crank end clearance space through the passage 48 to the interior of the cylinder between the piston 13 and the head end head 2, resulting in the flashing over of compressed fluid from the crank end clearance space to spontaneously super-charge the new charge sucked in behind the piston 13, reduction of the pressure of the crank end clearance space, including the passage 48, and equalization of the pressures on the two sides of the piston 13. Reverse, and return travel of the piston 13 continues the equalization of pressures on the two sides of the piston 13 until the port 50 of the passage 48 is closed by the face of the piston nearest the head 2. Further travel of the piston in its stroke effects re-expansion of the reduced pressure volume in the crank end clearance space down to the inlet pressure, the opening of the inlet valve 23, and the sucking in of a new charge through the inlet valve 23,

while on the opposite side of the piston 13, compression of the partially compressed fluid is taking place between the cylinder 1, the head 2 and the piston 13, followed by expulsion through the discharge valve 28, the opening of the port 49 and the passage 47 and a repetition of the cycle. Thus, by automatically by-passing the piston 13 effective upon its own travel, at or near the respective ends of its strokes, liberally sized inlet and discharge valves and passages may be employed to thereby reduce the losses through the valves, whereby earlier opening of the inlet valves occurs in each suction stroke, the volumetric efficiency is greatly increased, and the overall efficiency is higher than heretofore obtained.

Referring to Fig. 3, I provide a vertical compressor of the two cylinder, single acting, single stage type with the crank 51 to operate the elongated trunk piston 52, and at 180 degrees from the crank 51, the crank 53 is provided to operate the opposite elongated trunk piston 54. The cranks 51, 53 may be integrally forged with the crank shaft 55 and mounted in the bearings 56, 57, 58 supported by the crank case 59. The cylinder block 60, having the water jacket 61 may contain the two parallel cylinders 62, 63 and may be mounted directly upon the crank case 59. The piston 52 is shown connected by the crank 51 of the crank shaft 55 with the connecting rod 64, and the opposite piston 54 is shown connected by the crank 53 of the crank shaft 55 with the connecting rod 65. The cylinder head block 66, having the water jackets 67, houses the inlet valves 68, 69, their bonnets 70, 71, their studs 72, 73, the inlet opening 74 and the passages 75, 76, the block 66 is bolted to and supported by the cylinder block 60. The cylinder head block 66 also houses the discharge valves 140, 141, their studs 142, and such discharge valves communicate with the cylinders 62, 63 respectively and with the outlet opening 144, through the outlet passages 145, 146 respectively. The bonnets of the discharge valves 140, 141, are not shown, being similar to the bonnets 70, 71 of the inlet valves 68, 69. The inlet valves 68, 69 and the discharge valves 140, 141 are preferably of similar construction to corresponding valves of Fig. 1.

The cylinder 62 is connected with the cylinder 63 by the passage 77. The port 78 of the passage 77 is opened to communication with the passage 77 and the cylinder 63 above the piston 54 when the piston 52 is in its lowest position as shown. Upward travel of the piston 52 closes off communication between the cylinder 62 and the cylinder 63 following which compression and expulsion is effected within and from the cylinder 62. A simultaneous downward travel of the piston 54 effects the re-expanding of its clearance volume, the sucking in of a new charge, and then the opening of the port 82 and the passage 80, thus establishing communication through the port 81 and the cylinder 62 to effect the flashing over of the unexpelled compressed fluid remaining above the piston 52 after expulsion has ended, thus super-charging the new charge in the cylinder 63, thus reducing the pressure in the clearance space above the piston 52 and effecting a reduction in the loss of capacity due to the re-expansion of the clearance volume above the piston 52 as it travels downwardly, after which the cycle is repeated. A complete cycle of the piston 54 is harmonized at 180 degrees with the piston 52 and the phenomena which takes place 75

in the cylinder 63 is similar to that which takes place in the cylinder 62. The cycle in cylinder 63 is traced to include suction of the new charge upon downward travel of the piston 54, opening of the port 82 and spontaneous supercharging of the new charge above the piston 54, upward travel of the piston 54 effecting compression followed by expulsion or delivery, opening of the port 78 by the piston 52, the flash-over to the cylinder 62 of the clearance volume to reduce the pressure in the clearance volume above the piston 54, then, downward travel of the piston 54, upward travel of the piston 52, closing of the port 78 and the passage 77 by the piston 52, re-expansion of the reduced pressure clearance volume above the piston 54, the resultant earlier opening of the inlet valves above the piston 54, the consequent greater volumetric efficiency, and then alternating repetitions of the cycle in the opposite cylinders 62 and 63. Thus, the effect is in substance the same as that obtained in the double acting compressor of Figs. 1 and 2. The pulley 83 is mounted directly on the crank shaft 55 for driving the compressor with a belt from a suitable motor.

Referring to Fig. 4, the diagram illustrates and bounds by lines the compression cycle of the typical conventional prior art type of fluid compressor. The diagram is a pressure volume diagram, usually called an indicator diagram, with absolute pressures plotted as ordinates, and with volumes plotted as abscissas. In the diagram, A B C D A represents an ideal indicator card taken from a standard conventional type of an air compressor with clearance. In this case A G represents the stroke of the piston of the machine and C E represents the volume of the clearance, that is the volume between the face of the piston at the end of its stroke and the discharge valves, and consists of the actual volume between the piston and the cylinder head plus the volume of the ports and passages connecting the cylinder with the inlet and discharge valves. Air is discharged at the absolute pressure P_2 along B C and at point C the piston reverses in direction and the discharge valve closes. As the piston travels backward the volume of air represented by C E expands along C D until the absolute inlet pressure P_1 is reached at D when the inlet valve opens. It is evident that the actual volume drawn into the cylinder is now A D instead of the piston displacement A G and the ratio of A D to A G is called the volumetric efficiency of the compressor.

Referring to Fig. 5, similar points are shown on the diagram for comparison with the diagram shown in Fig. 4 and these similar points are denoted by the same letters, and also, additional points are shown by additional letters to differentiate between the diagrams according to Figs. 4 and 5, and, when these points are connected with lines, the boundary of the diagram, Fig. 5 is obtained. The diagram, Fig. 5 represents my new method of compressing a fluid and my new compression cycle characterizing my new method of compressing according to my invention in its most fundamental form. Tracing the pressure volume indicator card as shown on the diagram, Fig. 5, AIBCHJHDA represents an ideal indicator card according to my invention. In this case A G represents the stroke of the piston 13, Figs. 1 and 2, and C E represents the volume of the clearance 45, that is the volume between the face of the piston 13 at the end of its stroke and the discharge valve 28 and consists of the actual volume

between the piston 13 and the cylinder head 2 plus the volume of the ports and passages connecting the cylinder 1 with the inlet valve 22 and the discharge valve 28, plus the volume of the passage 47. Air is compressed adiabatically along the line I B and discharged or expelled at the discharge absolute pressure P_2 along B C and at the point C the piston 13 uncovers the port 49, delivery or expulsion ceases, the discharge valve 28 closes, the pressure in the clearance 45 drops vertically on this diagram spontaneously supercharging the new charge of free air on the opposite side of the piston 13. This vertical pressure drop is represented by the line C H, the pressure on both sides of the piston 13 are equalized on the constant pressure line H J at the super-charge absolute pressure P_3 after which the piston 13 reverses its direction of travel, line J H, and closes the port 49. As the piston 13 travels toward the head plate 3, the volume of air in the clearance 45 represented by the volume C E expands from the spontaneous- super-charged absolute pressure P_3 along the line H D until the absolute inlet pressure P_1 is reached at D when the inlet valve 22 opens. It is evident that the actual volume drawn into the cylinder 1 is A D and that the ratio of A D to the piston displacement A G is much greater than that of the diagram represented by Fig. 4. After suction has taken place along D A, the port 56, Fig. 2, is opened by the piston 13, the passage 48 by-passes the piston 13, and spontaneous super-charging from the vertical downward expansion of the clearance 46 on the opposite side of the piston suddenly and vertically increases the pressure between the piston 13, the head 2, and the cylinder 1 from the absolute inlet pressure P_1 along the line A I to the spontaneously super-charged absolute pressure P_3 from which the cycle is repeated. The operations of a double acting compressor as shown in Figs. 1 and 2, and also of a two cylinder single acting compressor as shown in Fig. 3 are harmonized and synchronized in the juxtaposed diagrams shown in Fig. 6.

Referring to Fig. 6, the pressure volume diagram 84 represents the phenomena which occur in the cylinder 1 between the piston 13 and the head plate 2, Figs. 1 and 2, and also in the cylinder 62 above the piston 52, Fig. 3. Simultaneously, the phenomena occurring in the cylinder 1 between the piston 13 and the head plate 3, Figs. 1 and 2, and in the cylinder 63 above the piston 54 of Fig. 3, are shown by the pressure volume diagram 85, Fig. 6. The two diagrams are placed in juxtaposed position with respect to each other, and the points are projected upon the circle 86 to simultaneously show how the phenomena as they occur on the opposite sides of the piston 13 are harmonized and synchronized, and to show the interdependence of the phenomena which occur on the opposite sides of the piston 13. The arrows in the diagrams 84, 85 show the direction of travel of the piston 13 in the cylinder 1. The simultaneous phenomena as they occur in the cycles on the opposite sides of the piston 13 are as follows:—Diagram 85, vertical downward expansion of clearance volume and flash-over to opposite side of piston, line kl' , diagram 84, vertical rise in pressure from spontaneous super-charging along line bc ;—Diagram 84, compression, line cd and expulsion, line de , diagram 85, re-expansion of clearance volume, line $l'g$ and suction, line gh ;—Diagram 84, vertical downward expansion of clearance and flash-over to opposite side of the piston, line ef' , diagram 85, vertical rise in pres-

sure from the inlet pressure, or spontaneous super-charging, line *hi*—Diagram 84, re-expansion of clearance volume, line *f'a*, suction, line *ab*, diagram 85, compression, line *ij*, and expulsion or delivery, line *jk*, which completes the cycle. The details of the phenomena of each of the diagrams 84, and 85 are the same as those more fully outlined in Fig. 5 with the accompanying description.

Thus, I have shown means for by-passing about the piston of a double acting compressor at or near the respective ends of its strokes, for periodically interconnecting the respective ends of the cylinder and similar means for interconnecting the two opposite compression ends of the respective pairs of cylinders of a single acting compressor at or near the respective ends of the strokes of the piston operating therein, to spontaneously super-charge the new charges sucked in to be compressed, to periodically equalize the pressures in opposite compression compartments, to cause earlier opening of the inlet valves and the sucking in of a larger charge to be compressed, all when operating at full capacity, and at the same time producing higher overall efficiency.

Referring to Fig. 7, I show the phenomena as they occur in the operation of compressors according to my invention, in which the beginning 30 of a suction stroke on one side of the piston 13, and the beginning of a compression and expulsion stroke on the other side of the piston 13 are both delayed and varied in length to vary the capacity continuously in increments in exact proportion 35 to the demand for compressed fluid to maintain a relatively constant pressure in the discharge pipe. Similar to the showings in Fig. 6, the two pressure volume indicator diagrams 87, 88 are placed in juxtaposed position with respect to each other, 40 and the points are projected upon the circle 89 to simultaneously show the phenomena synchronized as they occur on the opposite sides of a double acting piston, and to show how these 45 diagrams are bounded by lines in sequence and which are traced as follows:—Diagram 87, vertical downward expansion of the clearance volume and flash over to the opposite side of piston, line *en'*, diagram 88, vertical rise in pressure from the inlet pressure due to the spontaneous super-charging of the new charge along line *hi*;—Diagram 87, by-pass interconnecting the opposite ends of the cylinder is kept open to equalize the pressures on the opposite sides of the piston in a double acting compressor shown by the constant pressure line *nf*, and by the constant pressure line *io* in diagram 88, following which the by-pass interconnecting the opposite ends of the cylinder is closed in response to the action of a pressure responsive regulator;—Diagram 87, by-pass closed and consequent beginning of the delayed re-expansion of the clearance volume, line *fa*, and suction along the relatively short line *ab*, diagram 88, by-pass closed, and consequent delayed beginning of adiabatic compression 55 represented by the line *oj* which is followed by the relatively short delivery along the line *jk*;—The by-pass interconnecting the opposite ends of the cylinder is again opened, the pressures on the respective opposite sides of the piston in a double 60 acting compressor are again equalized, and as shown on diagram 88, vertical downward expansion of the clearance occurs along the line *kp'*, and the flash over to the opposite side of the piston spontaneously super-charges the newly 65 sucked in charge along the line *bc* of diagram 70 75

87;—The valve in the by-pass interconnecting the respective ends of the cylinder is periodically kept open to produce equal pressures on the respective sides of the piston along the lines *cm* of diagram 87, and *pl*, diagram 88. The by-pass 5 interconnecting the opposite ends of the cylinder is again closed following which adiabatic compression takes place along the line *md*, and delivery along the relatively short line *de* of diagram 10 87, while in diagram 88, re-expansion of the clearance from the spontaneously super-charged pressure down to the inlet pressure occurs along the line *lg*, the delayed opening of the inlet valve having taken place at the point *g*, after which suction of the partial capacity new charge occurs along the relatively shortened line *gh*, after 15 which the cycle is repeated. It will be understood that if the by-pass valve interconnecting the opposite ends of the cylinder is held open throughout the entire stroke of the piston, the 20 capacity of the compressor will be zero and no compression will take place, also if the by-pass interconnecting the ends of the cylinder is kept closed continuously, the capacity of the compressor will be 100%, and that varying capacities 25 as required are effected by closing the said by-pass valve at different points in the stroke of the piston corresponding to the variable requirements.

Figs. 8 and 9 show the compressor disclosed in 30 Figs. 1 and 2 of my invention with the added features of my invention which embody the means of varying the capacity exactly in proportion to the demand for compressed fluid according to the controlled cycle for compression of a fluid as particularly disclosed in Fig. 7 herein. Like numerals denote the same parts as shown in Figs. 1 and 2, and their description will not be repeated. In addition to the disclosure according to Figs. 1 and 2 of my invention, I provide according to 40 Figs. 8 and 9, means for periodically interconnecting the respective opposite ends of the cylinder 1, and means for periodically disconnecting the said respective ends of the cylinder 1, and pressure responsive means for controlling the 45 timing of the interconnecting and disconnecting of the said opposite ends of the cylinder 1, and the duration of time during each stroke of the piston 13 for which the said opposite ends of the cylinder 1 are interconnected and disconnected 50 to delay the beginning of, and make ineffective, a portion of each of the suction and compression strokes of the piston 13 to vary the quantity of compressed fluid sucked in through the inlet pipe 16 and delivered into the discharge pipe 39 in 55 exact proportion to the demand. It will be understood that when the demand for compressed fluid decreases, the pressure in the discharge pipe increases until the effective capacity of the compressor is reduced. Also, when the demand increases, the pressure in the discharge line decreases until the effective capacity of the compressor is increased. Therefore, I also provide 60 pressure responsive control means effective in operation in accordance with the required variations in capacity.

The cylinder 1 is provided with the by-pass passages 47 and 48 as disclosed in Figs. 1 and 2, and also with the by-pass passage 90 connecting with the cylinder 1 and the head plate 2 by the 70 passage 91, and connecting also with the opposite end of the cylinder 1, and the head plate 3 by the passage 92. The valve 93 is provided to periodically open and close the by-pass passage 90 in response to variations of pressure in varia- 75

tion with the demands upon the compressor, for variations in delivery. The valve 93 and the valve gear which operates it may be of the semi-rotative or Corliss type valve and valve gear, or, they may be of any other of the well known types of non-releasing valve gears and valve mechanisms which would be suitable for the requirements. When the valve 93 is opened and held open, the pressures on the two respective sides of the piston 13 are equalized to delay the beginning of adiabatic compression on the one side of the said piston 13 and to simultaneously delay the beginning of re-expansion of the clearance volume on the opposite side of the piston 13, both of which begin when the valve 93 is closed, all as shown in Fig. 7.

Referring to Fig. 8, the valve closing arm 94 is fixed onto the stem 95 of the valve 93 and connected by a rod 96 with the piston of a dash pot 97. The valve opening arm 98 is loosely mounted on the stem 95 of the valve 93 and travels independently of the arm 94. The trip cam 99 is pivoted to the arm 98, and the trip arm 100 is also pivoted to the arm 98 and has a pin 101 engaging with the cam 99. The latch block 102 is attached to the closing arm 94, and the latch block 103 is attached to the trip arm 100. The wrist lever 104, mounted on the bracket 105 is connected by the rod 106 with the opening arm 98. The wrist lever 104 is also connected by the rod 107 with the rocker 108, and by the rod 109 with the eccentric strap 110 and the eccentric 111, mounted on the auxiliary shaft 112 and which is operated at twice the speed of the crank shaft 5 by the gears 113 and 114 to operate in harmony with the successive strokes of the piston 13.

Referring to Fig. 10, an automatic regulator is provided which operates in response to changes in the pressure in the discharge pipe as shown, or it may be varied in application to operate in response to changes in the pressure in the inlet pipe for compressors used as vacuum pumps. The automatic regulator determines the points of tripping and closing the by-pass valve 93 if and after it has been opened. The regulator comprises a vertical cylinder 115, mounted on the bracket 116, a plunger 117 fitted in the lower end of the cylinder 115, a weighted sleeve 118 fitted and movable vertically on the cylinder 115, a spring 119 interposed between the plunger 117 and the upper end of the sleeve 118. A checking or retarding device may consist of the dash pot 120 fixed to the upper end of the sleeve 118, and a plunger 121, fixed to the stand 122 which is mounted on the bracket 116. The sleeve 118 may be adjustably weighted by the divided rings 123 to determine the pressure which the compressor is to maintain. The cylinder 115 is connected below the plunger 117 with the discharge pipe 39 by the pipe 124. The sleeve 118 is connected by crank arms 125 engaging a groove 126 see Fig. 8, and with a rocker shaft 127 supported by the stand 122. One arm of the L-lever 128, suspended by a bar 129 from the shaft 127, is connected by a rod 130 with a corresponding arm 131 on the shaft 127. The other arm 132 of the lever 128 is connected by the rod 133 with the trip cam 99. The bar 129 is connected by the rod 134 with the eccentric strap 135 of the eccentric 136 which is mounted upon the shaft 112 and driven by the shaft 5 through the gears 113, 114. The eccentric 111, through the rocker 109 and wrist lever 104, vibrates the valve opening arm 98 through a constant arc, and

opens the by-pass valve 93 at or near the end of each stroke of the piston 13 immediately following the end of expulsion of compressed fluid from the cylinder 1 if the cam 99 is in position to permit the engagement of the trip blocks 102, 103. 5 The times or points of tripping the blocks 102, 103 and the consequent closing of the by-pass valve 93 after being opened, is determined by the pressure regulator according to Fig. 10 which moves the cam 99 into position to disengage the trip blocks 102, 103 sooner or later according to the pressure exerted on the plunger 117. An increase in pressure in the discharge pipe 39 causes the trip blocks 102, 103 to be engaged longer and the by-pass valve 93 to be closed later to effect 15 reduced delivered capacity. A decrease in pressure in the discharge pipe causes the trip blocks 102, 103 to become disengaged earlier thus causing the relatively earlier closing of the by-pass valve 93 to increase the delivered capacity. The 20 limit of operation is reached when the trip blocks 102, 103 remain disengaged all of the time thus keeping the by-pass valve 93 closed continuously to effect full capacity, that is 100% delivery from the compressor all as otherwise disclosed 25 in the compression cycle according to Figs. 6 and 7 of my invention. In variable capacity compressors according to my invention, the compression line leading up to expulsion, and the expulsion which follows, and the pressure of 30 spontaneous super-charging caused by the flash-over past the piston 13 is determined from the normal volume of the clearances 45, and 46 and the other usual factors. The re-expansion of the clearances from the pressure of the said spontaneous super-charging down to the inlet pressure is based upon a variable clearance dependent upon the normal volume of the clearance space 45 or space 46, Figs. 1 and 2, plus 35 the volume swept through by the piston 13 up 40 to the time of the closing of the by-pass valve 93, Figs. 7, 8 and 9.

The displacement of a fluid compressor is the volume displaced by the net area of the piston in cubic feet per minute. The capacity of a 45 compressor is the actual amount of fluid in cubic feet per minute at inlet conditions which is compressed and delivered. Volumetric efficiency is the ratio of capacity to the displacement of a compressor. Other things being equal, the volumetric efficiency depends upon cylinder clearance and the absolute ratio of compression. The absolute ratio of compression is the ratio of the discharge pressure P_2 pounds absolute pressure divided by the inlet pressure P_1 pounds absolute 50 pressure and is expressed as R . The mean effective pressure is obtained from the indicator diagram, and when substituted in the well known formula, and also when considering volumetric efficiency, the indicated horse power per 100 cubic 55 feet of free fluid per minute actually delivered by the compressor is obtained for the adiabatic compression of the fluid. The actual indicated horse power of any compressor is greatly modified by the amount of fluid it actually delivers 60 in proportion to its piston displacement and, or volumetric efficiency. The method of calculating the horse power theoretically required to compress a fluid isothermally is also well known. The ratio of the theoretical isothermal horse power 65 to the actual horse power per 100 cubic feet of fluid actually compressed and delivered per minute is the basis for a real comparison between any two compressors. The relations between absolute pressures, absolute temperatures and vol- 70 75

umes in adiabatic compression and expansion may be found in the well known exponential equations.

No compressor ever delivers an amount of fluid equal to its piston displacement because of various effects of operating conditions, but primarily, because of the clearance loss. For the purpose of better showing the advantages of compressors according to my invention, and also to compare the power consumption and efficiencies of the same with the conventional prior type of compressor, similar structural features such as inlet and discharge valves and the like, are considered duplicated, and also operating conditions such as speed, inlet and discharge pressures, and inlet temperatures are considered the same for each type.

Whereas I have described my invention by reference to specific embodiments thereof, it will be understood that many modifications and changes may be made without departing from the spirit of the invention.

I claim:

1. In a compressor, the combination with a cylinder having clearance spaces, of a piston reciprocating therein, power operated means for operating said piston, inlet valve means, discharge valve means, inlet and discharge openings, and means associated with the said cylinder and the said piston for effecting reductions in the pressure of the fluid in the clearance spaces prior to the re-expansion of the fluid in the clearance spaces upon reverse travel of the said piston.

2. In a compressor, the combination with a cylinder having clearance spaces, of a piston reciprocating therein, power operated means for operating said piston, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston, and passage means respectively communicating with said clearance spaces and provided with openings located in the cylinder within the limit of travel of the piston and covered and uncovered by the piston at respective stages of its travel.

3. In a compressor, the combination with a cylinder having compression compartments, of a piston reciprocating therein, power operated means for operating said piston, inlet valve means, discharge valve means, inlet and discharge openings, and means associated with the compression compartments of said cylinder and the said piston for effecting spontaneous supercharging of the new charges to be compressed without the use of auxiliary compression compartments or auxiliary compressors.

4. In a compressor, the combination with a cylinder having clearance spaces, of a piston reciprocating therein, power operated means for operating said piston, inlet valve means, discharge valve means, inlet and discharge openings, and means for periodically equalizing the pressures in the clearance spaces and the cylinder at or near the respective ends of the strokes of the said piston, and for continuing said equalization of pressures during portions of the return strokes of the said piston.

5. In a compressor, the combination with a cylinder having compression compartments, of a piston reciprocating therein, power operated means for operating said piston, inlet valve

means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston and passage means respectively communicating with the compression compartments and respectively having ports communicating respectively with the inlet and discharge openings for automatically by-passing the said piston at or near the respective ends of the strokes of the said piston.

6. In a compressor, the combination with a cylinder having compression compartments, of a piston means reciprocating therein, power operated means for operating said piston, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston and passage means respectively communicating with the compression compartments and respectively having ports communicating respectively with the inlet and discharge openings, said ports being controlled by the operation of the said piston at or near the respective ends of the strokes of the said piston.

7. In a compressor, the combination with a cylinder means having compression compartments, of a piston reciprocating therein, power operated means for operating said piston, inlet valve means, discharge valve means, inlet and discharge openings, and passage means and port means for said passage means controlled by the operation of the said piston at or near the respective ends of the strokes of the said piston for periodically effecting equal pressures in the respective compression compartments and the cylinder means.

8. In a compressor, the combination with a cylinder having compression compartments, of a piston reciprocating therein, power operated means for operating said piston, inlet valve means, discharge valve means, inlet and discharge openings, and means associated with the said cylinder and the said piston for effecting reductions in the pressures in the compression compartments prior to the reversals of direction of travel of the said piston, re-expansion of the compression volumes from relatively low pressures to the inlet pressures, and relatively earlier opening of the said inlet valve means.

9. In a compressor, the combination with a cylinder having compression compartments, of a piston reciprocating therein, power operated means for operating said piston, inlet valve means, discharge valve means, inlet and discharge openings, and means associated with the said cylinder and the said piston for effecting reductions in the pressures in the compression compartments to a pressure greatly lower than the discharge pressure, re-expansion of the compression volumes from the relatively low pressure to the inlet pressure, relatively earlier opening of the inlet valves, the sucking in of relatively larger charges to be compressed, and higher volumetric efficiency.

10. In a compressor, the combination with a cylinder having compression compartments, of a piston reciprocating therein, power operated

- means for operating said piston, inlet valve means, discharge valve means, inlet and discharge openings, and means for by-passing the said piston at or near the respective ends of its strokes to effect flash-overs to the opposite compression compartments and simultaneous super-charging therein, reductions in the pressures in the compression compartments prior to the reversals of direction of travel of the said piston, re-expansion of the compression volumes from relatively low pressures, relatively earlier opening of the inlet valves, the sucking in of relatively larger charges to be compressed, and higher volumetric efficiency.
11. In a compressor, the combination with a cylinder having compression compartments, of a piston reciprocating therein, power operated means for operating said piston, inlet valve means, discharge valve means, inlet and discharge openings, and flash-over means controlled by the operation of the said piston for effecting equal pressures on both sides of the said piston at or near the respective ends of the strokes of the said piston, the pressure on the one side being the pressure to which the new charges of fluid have been initially increased in pressure by super-charging, the pressure on the other side of the said piston means being the reduced pressure from which re-expansion of the clearance volumes begin, to effect improved volumetric efficiency and improved isothermal compression efficiency.
12. In a compressor, the combination with a cylinder having compression compartments, of a piston reciprocating therein, power operated means for operating said piston, inlet valve means, discharge valve means, inlet and discharge openings, and flash-over means communicating respectively with the compression compartments and having ports communicating respectively with the inlet and discharge openings, said ports being controlled by the operation of the said piston for effecting equal pressures in the compression compartments at or near the respective ends of the strokes of the said piston, the pressure in the compression compartments being substantially the pressure to which the new charges of fluid to be compressed have been initially increased in pressure by super-charging, the pressure in the compression compartments being the reduced pressure from which re-expansion of the clearance volumes begin, to effect improved volumetric efficiency and improved isothermal compression efficiency.
13. In a compressor, the combination with a cylinder having compression compartments, of a piston reciprocating therein, power operated means for operating said piston, inlet valve means, discharge valve means, inlet and discharge openings, passage means communicating respectively with said compression compartments and having ports communicating respectively with said inlet and said discharge openings controlled by the operation of the said piston means to periodically interconnect and disconnect the respective ends of the cylinder to effect flash-overs from the compression compartments to simultaneously super-charge the new charges of fluid to be compressed on the opposite side of the said piston means and to reduce and equalize the pressure on the compression side of the said piston at the relatively small resultant pressure prior to the closing of the said port and passage means and the beginning of re-expansion of the compression volumes by reverse travel of the said piston.
14. In a compressor, the combination with a cylinder having compression compartments, of a piston reciprocating therein, power operated means for operating said piston, inlet valve means, discharge valve means, inlet and discharge openings, passage means respectively communicating with the compression compartments and respectively having ports communicating with said inlet and discharge openings, said ports being controlled by the operation of the said piston to periodically interconnect and disconnect the compression compartments to effect flash-overs from the compression compartments after delivery has ended to simultaneously super-charge the new charges of fluid to be compressed in the compression compartments and to reduce and equalize the pressures in the compression compartments at the relatively small resultant pressures prior to the closing of the said port and passage means and the beginning of re-expansion of the compression volumes by reverse travel of the said piston.
15. In a compressor, the combination with a cylinder having compression compartments, of a piston reciprocating therein, power operated means for operating said piston, inlet valve means, discharge valve means, inlet and discharge openings, passage means communicating with one of the compression compartments and having ports communicating with an inlet valve and passage means communicating with another of the compression compartments and having ports communicating with a discharge opening, said ports being respectively controlled by the operation of the said piston means to periodically interconnect and disconnect the ends of the said cylinder to effect flash-overs from the compression compartments respectively on the one side of the piston to equalize the pressures on the two respective sides of the said piston at the relatively low resultant pressure prior to the closing of one port of its passage means and the beginning of re-expansion of the clearance volumes to effect re-expansion of the compression volumes in relatively small portions of the return strokes of the said piston means, relatively earlier opening of the inlet valves, the sucking in of relatively large charges in proportion to the piston displacements, and relatively high volumetric efficiency.
16. In a compressor, the combination with a cylinder having compression compartments, of a piston reciprocating therein, power operated means for operating said piston, inlet valve means, discharge valve means, inlet and discharge openings, passage means communicating with one of the compression compartments and having ports communicating with an inlet opening and a second passage means communicating with another of the compression compartments and having ports communicating with a discharge opening, each of said ports being respectively controlled by the operation of the said piston to periodically interconnect and disconnect the compression compartments to effect flash-overs from the compression compartments and equalize the pressures in the compression compartments respectively and to effect re-expansion of the compression compartments in relatively small portions of the return strokes of the said piston, relatively earlier opening of the inlet valves, the sucking in of relatively large charges to be compressed in proportion to the piston displacement, and relatively high volumetric efficiency.

- high volumetric and isothermal compression efficiencies.
17. In a compressor, the combination of a pair of cylinders, pistons respectively reciprocated therein, power operated means, means for operating and synchronizing the operation of the said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston and passage means in each cylinder, means respectively communicating with the inlet and discharge openings and with the clearances of the cylinders respectively effective upon the operation of said pistons to periodically interconnect and disconnect the two respective cylinders at or near the ends of the strokes of their said piston.
18. In a compressor, the combination of a pair of cylinders, pistons respectively reciprocated therein, power operated means, means for operating and synchronizing the operation of the said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston and passage means in said cylinders respectively communicating with the inlet and discharge openings and having ports controlled by the operation of the said pistons respectively to periodically interconnect and disconnect the two respective cylinders at or near the ends of the strokes of the said pistons.
19. In a double acting compressor, the combination of a pair of cylinders, each having compression compartments, pistons respectively reciprocated therein, power operated means for operating said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston means for periodically equalizing the pressures in the compression compartments on the respective sides of each piston at or near the respective ends of its strokes, means for continuing the equalization of pressure in the compression compartments during portions of the strokes of said pistons, and pressure responsive means for controlling said continuing means to vary the delivered capacity of the compressor.
20. In a variable capacity compressor, the combination of a plurality of cylinders, each having compression compartments, pistons respectively reciprocated therein, power operated means for operating said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston and passage means for each cylinder respectively communicating with the inlet and discharge openings and having ports controlled by the operation of said pistons to by-pass the pistons, said passage means

including passages periodically interconnecting and disconnecting the opposite ends of the said cylinders.

21. In a variable capacity compressor, the combination of a plurality of cylinders, each having compression compartments, pistons respectively reciprocated therein, power operated means for operating said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston passage means for each cylinder communicating respectively with the inlet and discharge openings and further including passages respectively interconnecting and disconnecting the opposite ends of the said cylinders, and means for predetermining the effective period of operation of said passage means.

22. In a variable capacity compressor, the combination of a plurality of cylinders, each having compression compartments, pistons respectively reciprocated therein, power operated means for operating said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston passage means for each cylinder communicating respectively with the inlet and discharge openings and further including passages respectively interconnecting and disconnecting the opposite ends of the said cylinders, and pressure responsive means for predetermining the effective period of operation of said passage means.

23. In a variable capacity compressor, the combination of a plurality of cylinders, each having compression compartments, pistons respectively reciprocated therein, power operated means for operating said pistons, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston passage means for interconnecting and disconnecting the opposite ends of the said cylinders, valve means for said passage means, valve gearing for opening said valve means, and for closing said valve means during any portion of the return strokes of the said pistons, and pressure responsive means for controlling said valve gearing.

24. In a variable capacity compressor, the combination of a cylinder, having compression compartments, a piston reciprocated therein, power operated means for operating said piston, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston and passage means communicating with the inlet and discharge openings and with

the compression compartments respectively for decreasing the effective length of the respective strokes of the said piston and for increasing the effective volumes of the compression compartments.

25. In a variable capacity compressor, the combination of a cylinder, having compression compartments, a piston reciprocated therein, power operated means for operating said piston, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston passage means communicating with the inlet and discharge openings and with the compression compartments respectively for decreasing the effective length of the respective strokes of the said piston and for increasing the effective volumes of the compression compartments, and pressure responsive means for controlling the effective period of operation of said passage means.

26. In a compressor, the combination of a cylinder having compression compartments, a piston reciprocated therein, power operated means for operating said piston, inlet valve means, discharge valve means, inlet and discharge openings, said inlet openings communicating with said clearance spaces on opposite sides of the piston for all stages of position of the piston, said discharge openings communicating with said clearance spaces on opposite sides of the piston for all stages of position of the piston means for periodically equalizing the pressures in the compression compartments respectively at or near the respective ends of the strokes of the said piston means, and means for continuing the said equalization of pressures in the compression compartments respectively during a portion of the return stroke of said piston.

27. In a compressor, the combination with a cylinder having compression compartments, of a piston reciprocating therein, power operated means for operating said piston, inlet valve means, discharge valve means, inlet and discharge openings, said inlet openings communicating with clearance spaces between the ends of the cylinders and the ends of the piston on opposite sides of the piston for all stages of position of the piston, said discharge openings communicating with said clearance spaces on oppo-

site sides of the piston for all stages of position of the piston, and means associated with the compression compartments of said cylinder and the piston for periodically interconnecting and disconnecting the respective compression compartments with the interior of the cylinder when the said piston is at or near the respective ends of its stroke.

28. In a compressor, the combination with a cylinder having compression compartments, of a piston reciprocating therein, power operated means for operating said piston, inlet valve means, discharge valve means, inlet and discharge openings, said inlet openings communicating with said clearance spaces on opposite sides of the piston, for all stages of position of the piston, said discharge openings communicating with said clearance spaces on opposite sides of the piston for all stages of position of the piston, and means controlled by the operation of the said piston for effecting equal pressures on both sides of the said piston means at or near the respective ends of the strokes of the piston, said pressure equalizing means including a chamber arranged to communicate with an inlet opening and having ports communicating with the compression compartments, said ports being closed and opened by the piston.

29. In a compressor, the combination with a cylinder having compression compartments, of a piston reciprocating therein, power operated means for operating said piston, inlet valve means, discharge valve means, inlet and discharge openings, said inlet openings communicating with the clearance spaces on opposite sides of the piston for all stages of position of the piston, said discharge openings communicating with said clearance spaces on opposite sides of the piston for all stages of position of the piston, and means controlled by the operation of the said piston for periodically effecting equal pressures in the compression compartments of the cylinder, said pressure equalizing means including a chamber arranged to communicate with an inlet opening, said chamber having ports communicating respectively with the compression compartments, said pressure equalizing means further including a chamber arranged to communicate with a discharge opening and having ports arranged to communicate respectively with the compression compartments.

EVERETT W. SWARTWOUT.
